SPARK PLUG

Leslie H. Middleton and Delbert Henry
Stoltenberg, Toledo, Ohio

Application October 7, 1942, Serial No. 461,196

3 Claims. (Cl. 123—169)

1

This invention relates to spark plugs, more particularly to methods of positioning center electrodes in ceramic insulators for forming a seal therebetween.

The problem of holding and sealing a center electrode in the bore of a ceramic insulator core has generally involved the use of a shouldered bore in the insulator against which a shoulder on the center electrode rested with sealing material, either in the form of compacted powder or fused glass positioned above the shoulder on the electrode. Due to the refractory nature of the material of which the insulator is composed, it is difficult and impracticable to accurately position the shoulder in the bore after firing the ceramic insulator, and uneven shrinkage during firing causes wide variations in the longitudinal placement of the shoulder it formed before firing. This variation gives rise to manufacturing difficulties which are aggravated by the fact that the shoulder during firing often loses its sharpness and clear definition.

The present invention obviates these difficulties by providing a smooth bore in the insulator having substantially a uniform cross section into which a center electrode is inserted and held in a predetermined position with reference to the exterior of the insulator by locating from its external shoulder in the preferred embodiment. A novel holding means is provided to hold the center electrode in this predetermined position during the period in which a holding and sealing body of compacted granular material such as powdered talc or a mixture of powdered talc and comminuted metal, is packed into a space between the center electrode and the bore of the insulator. By establishing a predetermined relation between the external shoulder of the insulator and the firing tip of the center electrode, the spatial relation of the electrodes of the completely assembled spark plug may be easily controlled, thereby obviating final trimming of the firing tip of the center electrode, which if it is made of refractory material such as tungsten often presents difficult and expensive production problems.

The use of a smooth bore in the insulator simplifies the manufacture of the insulator and at the same time gives a stronger insulator. Its use also facilitates the assembling operations of the spark plug by giving more accurate control of the parts so that a smaller number of rejections is made possible.

It is therefore a principal object of this invention to provide an insulator for a spark plug hav-

2

ing a smooth bore of substantially uniform cross section into which a center electrode is positioned by a body of compacted powder.

It is a further object of this invention to provide a method of positioning a center electrode in a smooth bore of an insulator, wherein the insulator and the electrode are held externally in a predetermined relation during the compacting of a body of powder between the bore and the electrode to form a holding and sealing body.

It is a further object of this invention to position a center electrode in a smooth uniform bore of a ceramic insulator by a method wherein one end of the electrode is held in fixed, predetermined position with reference to the external shoulder of the insulator during the period in which a compacted body of powder is packed in position between the electrode and the bore of the insulator to form a holding and sealing body.

It is a further object of this invention to provide a method of sealing a center electrode in a ceramic insulator of a spark plug by a holding and sealing body of compacted granular material, packed between the electrode and uniform bore in the insulator.

Other objects and advantages of this invention relating to the arrangement, operation and function of the related elements of the structure, to various details of construction, to combinations of parts and to economies of manufacture, will be apparent to those skilled in the art upon consideration of the following description and appended claims, reference being had to the accompanying drawings forming a part of this specification wherein like reference characters designate corresponding parts in the several views.

Fig. 1 is an elevational view partly in section showing a jig utilizing the method of holding an insulator and electrode in predetermined relation during the period in which granular material is compacted in position.

Fig. 2 is a sectional elevation of an unshielded spark plug to which the invention has been applied.

Fig. 3 is a sectional elevation of a shielded spark plug to which the invention has been applied, and

Figs. 4 and 5 are sectional elevations of insulators and holding jigs illustrating modifications of the invention.

Referring to the drawings particularly to Fig. 1, a ceramic insulator 10 is provided which is constituted of a highly refractory insulating material such as sintered corundum or the like, having a longitudinal bore 11 which is smooth and

preferably given a uniform cross section throughout the insulator body. Adjacent a central location of the insulator 10 an enlargement 12 is provided which forms a pair of external shoulders 13 and 14 to cooperate with an inclosing metallic shell 15 as shown in Fig. 2 to form a completely assembled spark plug.

The shell 15 is provided on its lower end with a tubular threaded portion 16 by which the spark plug may be attached to the cylinder block of an internal combustion motor to which the plug is to be applied for use. An internal shoulder 17 is provided on the interior of the shell 15 to cooperate with the lower external shoulder 14 on the insulator to form a seat. A gasket 18 of relatively soft metal is positioned between the shoulders to form a leak-proof joint when the plug is completely assembled. On the upper end of the shell 15, a lip 19 is provided which is adapted to be turned in to form a holding portion to cooperate with the upper external shoulder 13 of the insulator to form a one-piece plug. In Fig. 2 on the right side of the drawing the lip is shown in its original form before being turned in as shown at 19a at the left side. A gasket 20 is provided to seat the inturned lip 19a on the shoulder 13. After the shoulder 19a is turned in, the plug may be given a "hot press," where the application of heat and pressure to the shell (shown schematically in Fig. 2), a portion between the lip 19a and the shoulder 17 is thermoplastically collapsed to form a leak-proof joint at the gasket 18. This process is well-known in the art and need not be described in further detail.

As has already been described, the central longitudinal bore 11 of the insulator is uniform in cross section which allows the use of a cylindrical center electrode 21, preferably formed of a metal having a coefficient of expansion matched to the coefficient of expansion of the insulator. For example if the insulator is made of aluminum oxide, the center wire or electrode may conveniently be made of nickel-iron alloy. To give the firing tip of the electrode, resistance to spark erosion, a piece of tungsten 21A may be welded in place adjacent the lower end of the insulator to provide a projecting tip to cooperate with a fixed electrode 22 (shown in Fig. 2) which may be conveniently brazed in position on a shoulder 23 on the lower end of the threaded portion 16 of the shell.

Inasmuch as the bore 11 in the insulator is smooth and the center electrode 21 is cylindrical, a separate means is provided to hold the two parts in a predetermined relation while a sealing and holding body 24, comprising a compacted body of granular material, is packed into position in a space 25 formed between a reduced portion 21a of the center electrode and the bore 11. A shoulder 26 is formed on the electrode 21 at the point where the reduced portion joins with the cylindrical portion which substantially fills the lower portion of the bore. The shoulder 26 forms an abutment against which the granulated material may be packed as shown in Fig. 1. Prior to the positioning of the holding and sealing body 24 in the space 25 cement is preferably positioned between the cylindrical portion of the electrode and the lower portion of the bore, although it is generally desirable to avoid the use of cement in the space 25 where the cement would interfere with the packing of the granular material.

In Fig. 1, a packing press or jig is illustrated which holds the center electrode 21 between a

socket 27 in a base member 28 whose depth is made adjustable by lock screw 29 and a spring pressed mandrel 30 positioned in a vertically-movable head 31. The head is movable through the agency of a rack and gear arrangement actuated by a manually operable lever 32, which rotates a gear 33 journaled in an upright 34 to cooperate with a rack 35 on the head 31. On the lower end of the head 31, a hollow ram 36 is provided having an external diameter slightly smaller than the bore 11 of the insulator 10, and an internal diameter slightly larger than the reduced portion 21a of the center electrode. The spring pressed mandrel 30 is adapted to slide vertically inside of the ram and is provided on its lower end with a reduced portion 30a which cooperates with a vertical bore 21b in the reduced portion 21a of the center electrode, so that the spring urging the mandrel downwardly will be enabled to hold the bottom tip of the center electrode 21 in the socket 27 of the base member.

The base member 28 is provided with a boss 28a concentric with the socket 27, having a series of bores 37, 38, and 39 all concentric with the socket 27, and adapted to closely fit the exterior of the spark plug insulator 10 to hold the same firmly in upright position. The shoulder 39a formed between the bores 38 and 39 is given the same contour as the lower shoulder 14 on the insulator 10 and forms a means of locating whereby the relation between the shoulder 14 and the lower tip end 21A of the center electrode is predetermined. This relation is adjustable through the action of the lock screw 29 which determines the depth of the socket 27. Any other exterior point on the insulator may be used as a locating point, as for example in Figs. 4 and 5, the tip of the insulator is used as the determining point. Other points will readily suggest themselves to those skilled in the art. The exterior shoulder 14 of the insulator is preferable as a locating point inasmuch as the dimensions of the shell are largely determined by the position of the internal shoulder 17, which will give better matching of the electrodes when the plug is completely assembled.

With the exact control of the tip projection, made possible by the use of device disclosed in Fig. 1, the relation of the electrodes at the firing tip can be predetermined so as to obviate undesired projection of the tungsten tip below the fixed electrode. If a projection of this kind occurs, it must be ground off by special methods inasmuch as tungsten is a very refractory material. These extra operations incur greater expense and even complete rejection of the assembled plug.

If desired a vertical fluting 40 may be provided on the center electrode, preferably adjacent the lower end thereof which provides a convenient method of centering the center electrode in the insulator bore. This method has the added advantage of allowing cement positioned between the center electrode and the bore to become more evenly distributed, which is essential to give a series of fabricated plugs more uniform heat ranges.

In order to position a center electrode in the bore of an insulator, the bore is first covered with a coating of cement which may be accomplished conveniently by completely filling the bore with cement. A swab is then temporarily attached to the upper end of the electrode and pushed through the bore from the firing tip, removing all but a thin layer of cement from

the bore. This removes the superfluous cement from the bore and yet leaves a relatively thin, uniformly distributed coating of cement between the bore and the larger portion of the electrode. The swab is then removed from the upper end of the electrode and a small perforated washer 41 either of rubber or asbestos or like material is positioned on the reduced portion of the electrode and pushed downwardly thereon until it rests on the shoulder 26 as shown in Figs. 1 and 2. This downward thrust of the washer 41 causes the perimeter of the washer to contact the wall of the bore 11 and by a "squeegee effect" moves substantially all the cement downwardly before it as it moves against the shoulder. The upper portion of the bore adjacent the reduced portion 21a of the electrode is thereafter substantially dry and free of cement so as not to interfere with the packing of granulated material such as powdered talc in the space 25.

The cement used for this purpose is preferably a cement which sets by a chemical reaction, rather than a cement which sets after the solvent evaporates, however such a cement may also be used if desired.

While the cement is still moist and "unset" the cemented assembly of the center electrode and insulator is positioned in the holder portion of the packing device shown in Fig. 1. The tip portion 21a of the center electrode is positioned in socket 27 and forced downwardly against the lock screw 29 and the external shoulder 14 of the insulator is thrust into contact with the shoulder 39a on the holder device to establish a fixed relation between the positions of the bottom tip 21a of the center electrode and the external shoulder 14 of the insulator. A small funnel member 42 preferably of magnetic material is positioned on the top of the insulator as shown in Fig. 1 by embracing a portion thereof to hold the funnel member firmly in position. The spring-pressed mandrel 30 is then brought into engagement with the upper end of the electrode by putting the tip 30a into the bore 21b of the electrode. This firmly urges the lower end or tip 21a against the lock screw 29.

With the parts in the position shown substantially in Fig. 1, powdered or comminuted material in granular form is poured into the funnel member 42 by any convenient means such as a cup 42a so that it falls by gravity into the space 25 in the vertically positioned insulator 10. An operator then actuates the handle 32 in a manner to advance the ram 36 downwardly into the space 25, where it contacts the loose powdered material and compacts it into position against the shoulder 26 on the electrode 21. After the first portion of the powdered material is compacted in position the ram 36 is again raised to above the funnel member 42 to allow a new portion of loose powder to fall into the space 25, whereupon this loose portion is compacted by lowering of the ram, and so forth until the necessary amount of powder has been compacted in position in the space 25 to form a holding and sealing body between the electrode and the bore of the insulator. An alternating current solenoid 43 may be conveniently positioned adjacent the funnel member 42 which may be of magnetic material, and provided with a spring member 44 to cause the funnel to be agitated to the desired degree so that the loose powder will readily fall into the space 25 when the ram 36 is in raised position. This agitation facilitates

packing and reduces the time required to accomplish the positioning of the compacted body.

The assembly is then removed from the holding device shown in Fig. 1, and the upper end of the compacted body is reamed out to a predetermined distance from the top of the insulator, a shouldered reamer being a convenient means to accomplish this purpose. A terminal tip 45 as shown in Fig. 2 is placed on the top of the electrode, having a depending flange 45a cooperating with the space 25, and the upper end of the electrode is peened to open the bore 21b to hold the tip 45 permanently in position. The completed assembly is then positioned in the shell 15 and the plug completed in the well known manner.

In Fig. 3 an aviation spark plug of the shielded type is shown to which the invention has been applied. This plug is of two-piece construction, having a lower shell portion 46 adapted to be attached to the cylinder of an internal combustion engine by a threaded portion 47, and having an upper sleeve portion 48 threadedly-attached to the shell portion 46. An insulator 49 is positioned between internal shoulder 50 in the shell portion and the lower end 48a of the sleeve portion, being provided with an intervening spring member 51 to give resiliency to the assembly. The sleeve portion is provided with a tubular insulator 52 as is well known in the art.

The insulator 49 is again provided with a smooth longitudinal bore 11 of uniform cross section in which again an electrode 21 is positioned as described before with reference to Figs. 1 and 2. The construction shown in Fig. 3 is substantially the same as that shown in Fig. 2 and is made by the same methods and will not be described again in detail. A flat terminal tip 53 is provided to facilitate connection, the tip being attached in a similar manner as described with reference to Fig. 2.

The details of construction of the aviation spark plug disclosed in Fig. 3, particularly with reference to the resilient member 51, are further disclosed and claimed in a copending application Serial No. 482,688, filed April 12, 1943, by Chester Cipriani and Carl Eaton, the application being assigned to the same assignee, and now having matured into Patent No. 2,389,597, granted

Nov. 27, 1945.

In Fig. 4 a modification of the invention is illustrated in which a cylindrical center electrode 55 is used in a smooth bore 56 in an insulator 57, the electrode being somewhat smaller than the bore to provide an annular space 58 between the parts into which is compacted a body 59 of granular material. The electrode 55 is again held between a socket 60 in a holding member 61, and a spring-pressed mandrel 62 as described in reference to Fig. 1, and the body 59 of compacted material again positioned in the bore as described before. A vertical fin 63 is provided above the socket 60 to embrace the tip of the electrode 55 and to fill the bottom end of the bore, to provide an abutment 64 against which the powder is compacted in position to form the body 59. When the body 59 is compacted in position the fin 63 will provide an annular vacant space into which a cement or readily fusible glass may be positioned to protect the compacted body from the hot gases in the cylinder of the engine. The locating position to determine the relation between the center electrode and the insulator may in this instance be the firing tip of the insulator.

In Fig. 5 a slight modification of Fig. 4 is shown in which the fin 63 is dispensed with and the powder is compacted in the lower portion of the insulator bore directly against the holding means 61a. Otherwise the modifications shown in Figs. 4 and 5 are substantially the same.

It is to be understood that the above detailed description of the present invention is intended to disclose an embodiment thereof to those skilled in the art, but that the invention is not to be construed as limited in its application to the details of construction and arrangement of parts illustrated in the accompanying drawings, since the invention is capable of being practiced and carried out in various ways without departing from the spirit of the invention. The language used in the specification relating to the operation and function of the elements of the invention is employed for purposes of description and not of limitation, and it is not intended to limit the scope of the following claims beyond the requirements of the prior art.

What is claimed:

1. In a spark plug, an insulator with a smooth uniform longitudinal bore of substantially uniform diameter, an electrode in the bore, a shoulder on the electrode between a larger portion of the electrode substantially filling the bore adjacent the lower end of the bore, and a smaller portion of the electrode adjacent the upper end of the bore, and a body of compacted granular material packed against the shoulder in the space between the bore of the insulator and the smaller end of the electrode to form a holding and sealing body between the electrode and the insulator.

2. In a spark plug, an insulator with a longitudinal bore of uniform cross-section throughout its length, a cylindrical electrode positioned in the bore substantially filling the bore adjacent the firing end of the insulator, a shoulder on the electrode adjacent the outer end of the insulator formed by a concentric portion of the

electrode of smaller cross section than the larger portion whereby a space is formed between the bore and the smaller portion of the electrode, and a body of compacted granular material positioned against the shoulder in the space between the smaller portion of the electrode and the bore to form a holding and sealing body between the electrode and the insulator.

3. In a spark plug, an insulator with a longitudinal bore of uniform cross section and external shoulders adapted to cooperate with an embracing metallic shell, a cylindrical electrode positioned in the bore substantially filling the bore and extending beyond the insulator to a predetermined position with reference to the external shoulders, a shoulder on the electrode adjacent the outer end of the insulator formed between the lower larger portion of the electrode and a smaller portion of less cross-sectional area than the bore to form a space between the electrode and the bore, and a body of compacted material positioned against the shoulder in the space between the smaller portion of the electrode and the bore to form a holding and sealing body between the electrode and the insulator.
